UNITED STATES PATENT OFFICE.

WALDEMAR KOPS, OF NEW YORK, N. Y., ASSIGNOR TO KOPS BROS., INC., OF NEW YORK,
N. Y., A CORPORATION OF NEW YORK.

APPAREL GARMENT.

Application filed June 25, 1927. Serial No. 201,324.

This invention relates to an apparel garment and more particularly to that type of garment in the nature of a corset which is adapted to surround the body and to extend from above the bust line to below the hips. The object of the invention is the provision of a garment of this type in which there is included a girdle so constructed as to cause the front portion thereof to function as an abdominal support and the back or rear portion thereof to function as a buttocks confiner.

To this end in carrying out the invention the garment made in accordance therewith comprises a body member preferably separable at one side where the edges are provided with means for connecting the one to the other and to extend from a point above the bust line to below the hips, the body member being constructed to include a girdle surrounding the body with the parts thereof connected at the front of the body and so designed that the back or rear portion of the girdle is incorporated with the lower portion of the body member of the garment, while the side and front portions are free from and underlie the adjacent portions of the body of the garment and are adapted to overlie the abdomen, the girdle being made to include inserts and straps of elastic material whereby the front portion thereof is adapted to support the abdomen and the back or rear portions to conform to and confine the buttocks with the overlying front portion of the body of the garment being unattached to the front portion of the girdle so as to produce a straight front effect, as will be hereinafter more particularly described.

In the drawing Figure 1 is a perspective view illustrating the use of a garment made in accordance with this invention.

Fig. 2 is a similar view on a slightly enlarged scale showing the parts of the body of the garment disconnected and folded back to illustrate the manner in which the front portions of the girdle or belt are connected, and

Fig. 3 is a plan on a still larger scale illustrating the garment and viewing the same from the inner side thereof.

Referring to the drawing the garment made in accordance with this invention comprises a body member which is adapted to extend around and conform to the body of

the wearer to a point or line above the busts to a point or line below the hips, and is preferably so constructed as to be open on one side. As illustrated, the garment is open at the left hand side, but as will be understood the parts may be reversed so that the garment will be open at the right hand side. The body of the garment, as illustrated, comprises a back member, side members, one of which is divided approximately centrally, and a front member. The back member, as shown, is constructed to include a back section 10 and lateral sections 11 and 12. The right hand side member as shown is made to include sections 13 and 14. The front member is indicated at 15, and the left hand side member as shown includes the sections 16 and 17. The section 10 of the back member is connected to the lateral section 11 thereof by a reinforcing strip 18 and suitable lines of stitching. Similarly, the central section 10 of the back member is connected to the lateral section 12 thereof by a reinforcing strip 19 and suitable lines of stitching. These reinforcing strips 18 and 19, as illustrated, comprise pockets for stays 20 and 21, which as illustrated, extend from points adjacent the upper edge of the garment to points adjacent the lower edge thereof. The lateral section 11 of the back member is connected to the section 14 of the right hand side member by a strip of reinforcing material 22 providing a pocket for suitable stays 23 which as illustrated extend from the upper edge of the garment to a point appreciably below the waist line. Similarly, on the left hand side of the garment the lateral section 12 of the back member is connected to the section 17 of the side member by a reinforcing strip 24 and suitable lines of stitching, the reinforcing strip forming a pocket for suitable stays 25 which correspond to the stays 23 and are of similar extent. The section 14 of the right hand side member is connected to the section 13 of this side member by a reinforcing strip 26 and suitable lines of stitching. The section 13 of the right hand side member is connected to the front member 15 by a reinforcing strip 27 and suitable lines of stitching. At its opposite side the front member 15 is connected to the section 16 of the left hand side member by a reinforcing strip 28 and suitable lines of stitching. It will be understood that the upper portion of the

garment have the sections thereof so formed as to conform with the contour of the body of the wearer.

The free edge of the section 16 of the left hand side member is provided with a reinforcing strip 29 secured in suitably spaced positions in which there are hooks indicated at 30. In a similar manner the free edge of the section 17 of the left hand side member is provided with a reinforcing strip 31 to which in spaced positions corresponding with the spacing of the hooks 30 there are eyes 32 each of which is adapted to be engaged by a hook 30 in securing the garment in position on the body of the wearer. In the lower portions of the section 14 of the right hand side member and the section 17 of the left hand side member there are elastic inserts indicated respectively at 33 and 34. At the forward edge of each of these elastic inserts the same is preferably curved to provide, as will be understood, for a greater stretch and tension at the lower portion of the garment which decreases upwardly so as to cause the garment to conform to the body of the wearer. The rearward edge of the elastic insert 33 is connected to the lateral section 11 of the back member by the reinforcing strip 22 and the same lines of stitching which connect this section 11 with the section 14. The forward edge of this elastic insert is connected to the adjacent edge of the section 14 by a reinforcing strip 35 and suitable lines of stitching. In a similar manner the rearward edge of the elastic insert 34 is connected to the section 12 by the reinforcing strip 24 and the lines of stitching which connect the section 17 of the left hand side member to the section 12, and the forward edge of this elastic insert is connected to the adjacent edge of the section 17 by a reinforcing strip 36 and lines of stitching. In the lower portion of the front section 15 and in a centrally disposed position is an inverted V shape elastic insert or gore 37 employed to assist in causing the lower portion of the garment to conform to the body and permitting the garment to yield with the body when in a seated position. Associated with the body of the garment as hereinbefore described, I employ a girdle adapted as stated to function as an abdominal support and buttocks retainer. This girdle is so associated with the body of the garment that the rear portions thereof are connected to the lower portions of the sections of the back member, and the side and front portions of the girdle are connected at their distant edges to the back portions thereof so as to complete the continuity of the girdle and to underlie the adjacent portions of the side sections and front section of the body of the garment. To this end in the lower portion of the section 10 of the back member there is a lining member 38.

This extends from the lower edge of the garment upwardly an appreciable distance and at its upper edge is connected to the section 10 by a line of stitching 38'. The sides of this lining 38 are connected in the lines of stitching which secure the reinforcing strips 18 and 19 in place, and the lower edge of the lining 38 is connected to the lower edge of the garment. Associated with the section 11 there is a lining member 39. At its lower edge this lining member 39 is secured to the lower edge of the garment, at its side edges it is connected to the reinforcing strips 18 and 22 by the same lines of stitching which connect these reinforcing strips to the body of the garment, while its upper edge is not connected to the section 11. A similar lining member 40 is associated in like manner with the section 12. The lining member 39 is preferably provided with a reinforcing strip 41 in which suitable stays 42 are placed, and similarly the lining member 40 is provided with a reinforcing strip 43 in which there are suitable stays 44. As illustrated, the upper edge 45 of the lining member 39 is inclined upwardly from the reinforcing strip 18 to the reinforcing strip 22, and the upper edge 46 of the lining 40 is inclined upwardly from the reinforcing strip 19 to the reinforcing strip 24. In the right hand side of the garment the girdle also includes a side member composed of sections 47 and 48. The lower portion of the adjacent connected edges of the sections 47 and 48 conforms more or less generally to the outer edge of the elastic insert 33 so as to be normally coextensive therewith and the adjacent edges of the sections 47 and 48 of this side member of the girdle are connected by a reinforcing strip 49 and suitable lines of stitching. In the left hand side of the garment the girdle is provided with a complementary side member made of sections indicated at 50 and 51 and the adjacent edges of which are connected by a reinforcing strip 52 and suitable lines of stitching. This line of connection conforms in the lower portion thereof to the outer edge of the elastic insert 34 so as to be normally substantially coextensive therewith. The lower edge of the sections 47 and 48 tapers upwardly as indicated at 53 so as to extend from the lower edge of the back member to the lower edge of the front member of the girdle and the upper edge of these sections extends downwardly as indicated at 54, and in a similar manner the lower edge of the sections 50 and 51 tapers upwardly as indicated at 55, the upper edge thereof tapers downwardly as indicated at 56.

The girdle also includes a front section which is open centrally and includes right and left hand members. The right hand member of the front of the girdle comprises a section 57 of inelastic material and an in-

sert 58 of elastic material extending from the upper to the lower edges of this section of the girdle. The section 57 also includes a front steel 59 fitted with sockets 60 and 5 extending from the upper edge of the front of the girdle an appreciable distance downwardly and terminating distant from the lower edge of the girdle below which this front edge of this member of the girdle is 10 fitted with suitable hooks 61. As illustrated, the section 57 is preferably provided with reinforcing strips 62 and 63 providing pockets for stays indicated at 64 and 65. In this front member of the girdle there is also 15 a front uplift strap made of elastic material as indicated at 66. The forward edge of this strap is connected to the lower free edge of this front section preferably below the front steel, and the rearward edge is 20 connected to the reinforcing strip and lines of stitching by which this front member is connected to the side members composed of the sections 47 and 48. The front member of the girdle at the left hand side of the garment is similarly constructed and includes a section 67 of inelastic material, an 25 insert 68 of elastic material extending from the upper to the lower edges of this portion of the girdle. Along the free edge of this 30 front member of the girdle there is a front steel 69 provided with a series of studs 70 adapted to engage with the sockets 60 to connect these members of the girdle, and below the steel 69 the free edge of this member 35 of the girdle is provided with eyes 71 adapted to engage with the hooks 61 to secure the lower portions of these members of the girdle to one another. The section 67 is 40 preferably fitted with reinforcing strips 72, 73, making provision for pockets for suitable stays 74 and 75. In this front member of the girdle there is also an uplift strap 76. Also 45 complementary to the uplift strap 66. Also as illustrated, the reinforcing strip, which, together with suitable lines of stitching, connects the section 48 with the elastic insert 58, makes provision for a pocket in which there is a suitable stay or stays 77, and in like manner, the reinforcing strip which 50 connects the section 51 with the elastic insert 68 makes provision for a pocket in which there is placed a suitable stay or stays 78.

The lower edge of the back of the garment is provided with suitable hose supporters 79 and 80. The lower edge of the front member of the girdle is provided with hose supporters as indicated at 81, 82, and in 55 suitably spaced positions the lower edges of the side sections are provided with hose supporters as indicated at 83 and 84. The garment may furthermore be provided with the usual shoulder straps 85 and 86. Furthermore, in the front of the garment and 60 preferably coextensive circumferentially of the front section 15, I prefer to employ a diaphragm strap 87. This, as illustrated, is connected at its distant edges in the lines of stitching which connect the reinforcing strip 27 to the sections 13 and 15, and the reinforcing strip 28 to the sections 15 and 16. At its upper and lower edges this diaphragm strap is not connected to the front member or section 15.

As will now be understood, the body 75 member of the garment surrounds the body of the wearer, and as illustrated, is preferably secured in place by connecting the edges of the garment on the left hand side thereof, while the girdle as described is 80 adapted at the lower rear portion thereof to conform to the buttocks of the wearer, and the front of the girdle to overlie and support the abdomen of the wearer, the upwardly inclined edges 53 and 55 extending 85 over the sides of the body so that the lower edges of the front sections conform to the groin line, the elastic inserts 58 and 68 providing the required circumferential tension, while the elastic straps 66 and 76 provide 90 the necessary uplift effect for the abdominal support, and these tensions together with those of the inserts 33 and 34 cause the lower rear portions of the girdle and the body of the garment to conform to the buttocks, as 95 hereinbefore stated. It will also be apparent that in view of the construction of the front section of the garment this will overlie the front section of the girdle more or less independently thereof and will function 100 to provide a straight front effect. Furthermore, as hereinbefore stated, in addition to the coaction with the lower portions of the girdle to cause the same to conform to the buttocks, the elastic inserts 33 and 34 cause 105 the body of the garment to conform to the body of the wearer over the hip portions thereof.

I claim as my invention:

1. In an apparel garment, a body member 110 adapted to surround the body of the wearer from a point above the busts to a point below the buttocks, the said body member including a back section, an abdominal support comprising sections of inelastic and elastic 115 material adapted to extend across the abdomen of the wearer, and side sections of inelastic material connected at their forward edges to the distant edges of the abdominal support and at their rearward edges to the 120 edges of the back section of the body member, the lower edges of the side sections extending downwardly from the lower edge portions of the abdominal support to substantially the lower edge of the lower side 125 portions of the back section of the body member whereby the tension exerted by the elastic sections of the abdominal support is transmitted through the lower portion of 130 the said side sections to the lower portion of

the back section of the body member to cause the same to conform to and retain the buttocks of the wearer.

2. In an apparel garment, a body member adapted to surround the body of the wearer from a line above the busts to a line below the buttocks, the said body member including a back section, an abdominal support comprising a front section of inelastic material and lateral sections of elastic material adapted to overlie the abdomen of the wearer, uplift straps of elastic material extending from the lower front portion of the abdominal strap to the distant edges thereof, and side sections of inelastic material connected at their forward edges to the distant edges of the elastic sections of the abdominal

support and at their rearward edges to the side edges of the back section of the body member, the lower edges of the said side sections extending downwardly from the lower end portions of the abdominal support to substantially the lower edge of the lower side portions of the back section of the body member whereby the tension exerted by the elastic sections of the abdominal support is transmitted thru the lower portions of the said side sections to the lower portion of the back section of the body member to cause the same to conform to and retain the buttocks of the wearer.

Signed by me this 15th day of June, 1927.

WALDEMAR KOPS.
